MACHINE FOR APPLYING PRESSURE TO
SHOE BOTTOMSAndrew Eppler, Jr., Lynn, Mass., assignor to
United Shoe Machinery Corporation, Flemington,
N. J., a corporation of New Jersey

Application June 5, 1951, Serial No. 229,979

4 Claims. (Cl. 12—33)

1

This invention relates to machines for use in the manufacture of shoes, and more particularly to machines for applying pressure to shoe bottoms.

Machines for this purpose generally include a sole-supporting pad and heel and toe abutments engageable with the toe portion of a shoe and the cone of a last in the shoe for supporting the shoe and last against the pressure of the pad. The machines are frequently called upon to operate on shoes of various styles and sizes and it may be necessary frequently to adjust the heightwise positions of the heel and toe abutments to accommodate the various styles and sizes of shoes to be operated upon.

It is an object of the invention to provide, in a machine of the type characterized above, improved means for supporting the heel and toe abutments arranged to permit rapid adjustment of one or both of the abutments with a minimum of effort on the part of the operator. To this end and in accordance with a feature of the invention, each abutment is carried by a rack mounted for vertical adjustment in a support having teeth cooperating with those on the rack for locking the rack and abutment in any one of a plurality of heightwise positions. The teeth of the rack are normally maintained in engagement with the teeth on the support by a vertically movable cam plate which acts to force the rack toward the teeth on the support when the cam plate is moved downwardly. If the plate is moved upwardly, the plate and the rack may be moved away from the teeth on the support to free the rack for vertical adjustment which is readily effected by the operator after which the plate is depressed to lock the rack in adjusted position within the support.

The above and other features of the invention including various details of construction and novel combinations of parts will now be described by reference to the drawings and pointed out in the claims.

In the drawings,

Fig. 1 is a front elevation, partly in section, illustrating the work-engaging parts of one form of machine in which the invention is embodied;

Fig. 2 is a plan view, partly in section, of the upper portion of the mechanism shown in Fig. 1; and

Fig. 3 is a section on the line III—III of Fig. 1.

The invention is illustrated as embodied in a machine of the type shown and described in Letters Patent of the United States 1,549,243 granted

August 11, 1925, on an application of E. E. Wink-

2

ley. The machine includes a pad box 10 carrying a sole-supporting pad 12, the pad and pad box being pivoted at 14 on frames 16 mounted for vertical sliding movement on rods 18. Mechanism is provided for moving the pad and pad box vertically to carry an assembled shoe and outsole upwardly into engagement with the heel and toe abutments 20, 22 respectively. The heel abutment 20 is illustrated as being in the form of a flat plate engageable with the cone of a last in the shoe although it will be understood that this abutment may be provided with a spindle arranged to enter the spindle hole in the cone of the last.

For supporting the heel and toe abutments, a crosshead 24 is secured to the upper ends of the rods 18 and carries a pair of supports 26, 28 which are slidable thereon lengthwise of the pad 12. To the underside of the crosshead 24 is secured a plate 30 and the side walls of the supports 26 and 28 have inwardly extending flanges 32 (Fig. 2) at their upper ends engageable with the top surfaces of the plate 30 whereby the supports 26 and 28 may be slid along the plate to locate the supports in the desired positions lengthwise of a shoe on the pad. As illustrated in Fig. 2, the supports 26 and 28 are interconnected so that they will move equally in opposite directions. For this purpose a lever 34 is pivoted at 36 in the central portion of the crosshead 24 and the outer ends of the lever are connected by links 38, 40 to the supports 26, 28 respectively. The upper ends of the supports are provided with several tapped holes 42 so that the links may be connected in any one of several positions along the supports. As one support is moved lengthwise of the crosshead it will be understood that the other support will be similarly moved but in an opposite direction. The supports carry blocks 44 urged by springs 46 into engagement with the adjacent face of the plate 30 to hold the supports against unintentional movement lengthwise of the crosshead. The action of the springs 46 may be adjusted by screws 48 to vary the action of the blocks 44.

As shown in Fig. 3 the supports are generally U-shaped in horizontal section and secured within the base of the U is a rack plate 50. The heel and toe abutments are carried by racks 52 having teeth engageable with the teeth on the fixed rack plates 50 so that with the parts in the positions shown in Fig. 1 a rigid connection is formed between the racks 52 carrying the abutments and the supports 26, 28.

For holding the racks 52 in locking engage-

ment with the rack plates 50, cam plates 54 are provided. Pins 56 are journaled in the side walls of the supports 26, 28 and extend therebetween and are provided with slabbed-off portions forming flat faces arranged to engage the adjacent surfaces of the cam plates 54. These cam plates 54 carry pins 58 having heads 60 which fit in T-shaped slots 62 (Fig. 3) extending vertically in the adjacent portions of the racks 52. The cam plates 54 have vertical surfaces 64 which, with the parts in the positions illustrated, engage the flat faces of the pins 56 and maintain the racks 52 in locking engagement with the rack plates 50. Just below the vertical surfaces 64 of the cam plates 54 are inclined surfaces 66 which permit the cam plates 54 to be moved outwardly when the plates are moved upwardly. For thus moving the cam plates they are provided with knobs 68 conveniently located for engagement by the operator. By reason of the connection afforded by the heads 60 of the pins 58 between the cam plates and the racks it will be apparent that upon moving the cam plates 54 upwardly and outwardly the racks 52 are moved away from the rack plates 50. At this time the pins 56 will turn slightly so that the flat faces of the pins will engage the inclined surfaces of the cam plates and these surfaces are so formed that the outward movement imparted by the operator to the racks 52 is sufficient to disengage the teeth of the racks 52 from the teeth of the rack plates 50.

When thus disengaged the abutments may readily be moved vertically to the desired heightwise positions by the operator whereupon the cam plates 54 are moved downwardly and forced inwardly at the same time by their engagement with the pins 56 to lock the racks 52 to the rack plates 50 in the proper positions of adjustment. Suitable indicia may be provided on the racks 52 to assist the operator in positioning the abutments in the proper heightwise positions in accordance with the particular size or style of shoe to be operated upon. When the cam plates are returned to their lowermost positions as illustrated in Fig. 1 the inclined surfaces 66, in moving downwardly with respect to the pins 56, exert a cam action on the flat faces moving the pins so that the flat faces are vertically disposed as illustrated and the cam plates 54 are securely held against unintentional displacement. Thus the racks 52 are rigidly held in engagement with the rack plates 50 carried by the supports 26, 28.

Provision is made for preventing the racks 52 from dropping entirely out of the supports 26, 28 when they are disengaged from the rack plates 50 by upward and outward movements of the cam plates 54. For this purpose the upper portions of the racks 52 have formed in their front faces elongated recesses 70 adapted to receive pins 72 (Fig. 3) which pass through bosses 74 formed in the front walls of the supports 26, 28. To the outer ends of the pins 72 are secured knobs 76 which normally seat against adjacent surfaces of the bosses 74 and are held in these positions by springs 78 acting against collars 80 secured to the pins. The pins 72 are smaller in diameter than the width of the recesses 70 thus permitting lateral movement of the racks 52 without interfering with the disengagement of the teeth thereon from the teeth on the rack plates 50. The recesses are sufficient in length to permit the racks to be adjusted throughout the desired range but engagement of the shoulders formed at the upper end of the

5 recesses with the pins will prevent the racks from dropping out of the supports when released from locking engagement with the rack plates.

Should it be desired to remove the racks with the abutments entirely from the supports, the pins 72 may be withdrawn from the recesses 70 by exerting an outward force on the knobs 76 against the action of the springs 78. The bosses 74 are provided with horizontally extending slots 82 adapted to receive pins 84 carried by the knobs 76 with the pins 72 in operative positions with respect to the racks 52. Upon pulling the knobs and the pins outwardly until the pins 84 are out of engagement with the slots 82 the knobs 76 may be turned to carry the pins 84 into engagement with the outer surfaces of the bosses 74 thus locking the pins 72 out of operative relation to the racks 52, facilitating replacement of the racks.

From the above it will be seen that the heel and toe abutments may be easily and rapidly adjusted heightwise of the pad 12 by the operator in accordance with the size and style of shoe to be operated upon, the adjustment being effected merely by lifting the cam plates 54 and moving them away from the rack plates 50 and then moving the racks until the abutments are in the desired heightwise positions whereupon they are securely locked in positions by moving the cam plates 54 downwardly during which movements they are automatically urged inwardly to force the racks 52 into locking engagement with the rack plates 50. Because of the large number of teeth on the racks which are in engagement with the rack plates the connection between the racks and the supports is sufficiently strong to withstand the heavy upward forces which are applied during upward movement of the pad box in the sole-laying or sole-attaching operation.

Having thus described my invention, what I claim as new and desire to secure by Letters Patent of the United States is:

1. In a machine for applying pressure to shoe bottoms, a sole-supporting pad, means for supporting a shoe and last against the pressure of said pad comprising an abutment, a vertically adjustable rack carrying said abutment, a support for said rack, a rack bar carried by said support cooperating with the rack to lock the rack against vertical movement relatively to said support, means for moving the rack laterally out of locking engagement with the rack bar to permit vertical adjustment of the rack and of the abutment carried thereby, said means comprising a vertically movable cam plate carried by said support, means connecting the cam plate and the rack for conjoint movements toward and from the rack bar while permitting relative vertical movements between the plate and the rack, and means cooperating with the cam plate for moving the cam plate and the rack in a direction to cause locking engagement of the rack with the rack bar in response to vertical movement of the cam plate in one direction.

2. In a machine for applying pressure to shoe bottoms, a sole-supporting pad, means for supporting a shoe and last against the pressure of said pad comprising an abutment, a vertically adjustable rack carrying said abutment, a support for said rack, a rack bar carried by said support cooperating with the rack to lock the rack against vertical movement relatively to said support, means for moving the rack laterally out of locking engagement with the rack bar to per-

mit vertical adjustment of the rack and of the abutment carried thereby, said means comprising a vertically movable cam plate carried by said support, means connecting the cam plate and the rack for conjoint movements toward and from the rack bar while permitting relative vertical movements between the plate and the rack, said cam plate having cam surfaces inclined downwardly toward the rack bar, and pins carried by said support having flat surfaces arranged for engagement with the inclined surfaces of the cam plate whereby the cam plate and the rack are urged toward the rack bar in response to downward movement of the cam plate by the operator.

3. In a machine for applying pressure to shoe bottoms, a sole-supporting pad, means for supporting a shoe and last against the pressure of said pad comprising an abutment, a vertically adjustable rack carrying said abutment, a support for said rack, a rack bar carried by said support cooperating with the rack to lock the rack against vertical movement relatively to said support, means for moving the rack laterally out of locking engagement with the rack bar to permit vertical adjustment of the rack and of the abutment carried thereby, said means comprising a vertically movable cam plate carried by said support, means connecting the cam plate and the rack for conjoint movements while permitting relative vertical movements between the plate and the rack, said cam plate having cam surfaces inclined downwardly toward the rack bar, and pins rotatably carried by said support and having flat surfaces arranged for engagement with the inclined surfaces of the cam plate whereby the cam plate and the rack are urged toward the rack bar in response to downward movement of

the cam plate by the operator, said cam plate having vertical surfaces above and adjacent to said inclined surfaces arranged for engagement with the flat faces of said pins thereby preventing unintentional lateral displacement of the rack out of locking engagement with the rack bar.

4. In a machine for applying pressure to shoe bottoms, a sole-supporting pad, means for supporting a shoe and last against the pressure of said pad comprising an abutment, a vertically movable rack carrying said abutment, a support for said rack, a rack bar carried by said support and cooperating with said rack to lock the rack against vertical movement in the support, a vertically extending T-slot in the face of said rack opposite to the face having rack teeth, a pin having a head slidable in said slot, a cam plate carrying said pin for movement vertically with respect to the rack, and means carried by the support cooperating with said cam plate for moving the cam plate and the rack as a unit toward the rack bar in response to downward movement of the cam plate while permitting movement of the cam plate and rack out of locking engagement with the rack bar upon upward movement of said cam plate.
